—FIG. 2.—

UNITED STATES PATENT OFFICE.

GEORGE W. CHURCH, OF STAMFORD, CONNECTICUT, ASSIGNOR TO R. HOE AND CO., OF NEW YORK, N. Y., A CORPORATION OF NEW YORK.

PAPER-ROLL-DRIVING MECHANISM.

1,093,913.

Specification of Letters Patent. Patented Apr. 21, 1914.

Application filed July 23, 1910. Serial No. 573,540.

To all whom it may concern:

Be it known that I, GEORGE W. CHURCH, a citizen of the United States, residing at Stamford, county of Fairfield, and State of Connecticut, have invented certain new and useful Improvements in Paper-Roll-Driving Mechanism, fully described and represented in the following specification and the accompanying drawings, forming a part of 10 the same.

This invention relates to improvements in paper roll driving mechanisms for printing and similar machines.

In an application filed by Robert Hoe, 15 May 11, 1910, Ser. No. 560,567, there is disclosed a driving mechanism for paper rolls of printing and similar machines which includes a continuously running driver roll, the driving engagement between the driver 20 roll and the paper roll being maintained as the paper roll decreases in size. While the mechanism disclosed in said application is efficient under certain conditions, it sometimes happens that the tension on the 25 web which is being pulled off the web roll varies due to slight variations in the demands made on the roll by the mechanism of the printing machine. In some cases, the stretch of the web will take care of the 30 variations referred to, but, in other cases, particularly where the web is composed of comparatively stiff and hard stock, the web has a tendency to break.

The present invention has for its object 35 to produce an improved web feeding mechanism for printing and similar machines in which there is employed a continuously running driver with which the web roll is maintained in constant engagement, the 40 construction including mechanism by which the surface speed of the driver is automatically varied.

A further object of the invention is to 45 produce an improved web roll driving mechanism for which there is employed a continuously running driver with which the web roll is maintained in constant engagement, the construction including mechanism by which the surface speed of the 50 driver is automatically varied, in accordance with the variations in tension of the web pulled off the roll.

With these and other objects not specifically referred to in view, the invention consists in certain constructions and in certain

parts, improvements and combinations as will be hereinafter fully described and then specifically pointed out.

Referring to the accompanying drawings:—Figure 1 is a plan view, partly in section, of a roll driving mechanism embodying the invention. Fig. 2 is a side elevation of part of the construction illustrated in Fig. 1, showing more particularly the connections between the tension and the driver. Fig. 3 is a detail front view, partly in section, of a part of the construction illustrated in Fig. 2.

Referring to the drawings which illustrate one embodiment of the invention, 1 70 indicates the side frames of the machine. Machines embodying the invention will include a continuously running driver so constructed that its surface speed may be varied. In the best constructions embodying the invention, the driver will consist of a sectional roll constructed so that it may contract or expand as required to vary its surface speed. In the particular construction illustrated, the driver roll 2 is mounted 80 on a shaft 3 provided with a driving gear 4 which may be suitably geared with any moving part of the machine, so that the driver may be driven at a surface speed which corresponds as nearly as possible with 85 the surface speed of the printing cylinders.

In the particular construction illustrated, provision is made for driving a plurality of rolls from one driver, two rolls being 90 marked 5. The driver is so located as to engage the exterior surface of the paper roll or rolls, and provision is made for maintaining engagement between the driver and the roll or rolls as the rolls decrease in size. 95 The particular means by which the engagement between the driver and the paper rolls is maintained may be varied within wide limits. In the particular construction illustrated, however, there is provided a source 100 of fluid under pressure which is utilized for this purpose.

When fluid under pressure is employed to maintain the driving relation between the driver and the paper roll the character of 105 the source from which the fluid is obtained may be varied. In the particular construction illustrated, there is provided an accumulator or reservoir 6 in which the fluid under pressure is maintained, the fluid en- 110

tering the reservoir by means of a pipe 7, a suitable regulating valve, indicated at 8, being provided, if desired, to control the inflow of the valve. As shown, this reservoir is provided with an outlet pipe 9 which, by means of two branches 10, conveys the fluid under pressure to piston chambers 11 mounted on the frame of the machine. In the particular construction shown, inasmuch as two rolls are illustrated, two pairs of these piston chambers are employed, but as the construction of these chambers and their connections are identical, only one pair will be described. Located in these piston chambers are pistons (not shown) which are connected by rods 13 with the bearings 14 in which the paper roll shaft 5 is mounted. These bearings are shown as movable on ways 15 formed on the machine frame, the 10 bearings and ways forming a support for the roll. While the mechanism described furnishes a simple and efficient means for supporting the roll, the construction may be varied in this respect, if desired. The pipes 10 are provided with branches 16, 17, so that the fluid may be admitted to either side of the pistons, the flow being controlled by suitable cocks 18. When, as in the construction shown, two pairs of piston chambers are employed, what may be termed the second pair of pistons may be supplied with fluid pressure by branch pipes 19. By the construction described, the paper rolls, or either of them, may be brought into driving 20 relation and maintained in such relation by the driver.

Constructions embodying the invention will, as has been pointed out, include means for varying the surface speed of the driver 25 and as has been stated, in the best constructions embodying the invention, the driver roll will be made up of sections to enable this to be readily effected. In the particular construction illustrated, the driver roll 2 is composed of a plurality of segmental surfaces 30. The means by which the surface speed of the driver is varied may differ widely in character and will, of course, differ according to the construction of 30 driver which may be adopted in carrying the invention into effect. Such means, however, will usually include a suitable controller which may, as in the particular construction illustrated, consist of a cone 31 mounted to slide on the shaft 3, the cone being provided with a collar 32 engaged by an operating yoke 33. In order to insure the positive operation of the sections 30 by the controller, the cone 31, when a cone is 35 employed, may be provided with dove-tailed ribs 34 engaging corresponding dove-tailed recesses on the interior of the segmental sections 30. It will be understood that, in the best constructions embodying the invention, when the driver comprises a roll made

up of segmental sections, the controller will comprise a cone and suitable operating devices therefor at each end of the driver. Inasmuch, however, as the construction may be identical, only one cone and one set of 70 driving connections are shown.

The operating devices for the driver, whatever may be its construction, will be of such a character as to vary the surface speed of the driver as the tension on the 75 web varies. While the means by which this result is accomplished may be varied, in the particular construction illustrated, there is provided a tension roll 35 over which the web is led from the web roll, this tension roll, in the particular construction illustrated, being supported in sliding boxes 36 moving on guides 37 in recesses in the frame, the boxes resting on springs 38. A guide roll, as 39, is provided over which the web also runs, this roll being located in such relation to the roll 35 that any increase or decrease in the tension of the web will operate to vary the position of the roll 35, the springs 38 permitting this variation. 80 The tension of these springs may be controlled by screws 39', 40 and lock nuts 41.

In the particular construction illustrated, the movements of the roll 35 caused by the variations in tension of the web, are utilized 95 to vary the surface speed of the driver. While the connections by which this is accomplished may be varied, in the particular construction illustrated, there are provided connecting rods 42 secured at 43 to the 100 boxes of the tension roll 35, and at 44 to levers 45 which control the cocks in branch pipes 46 connecting with the branches 19 which are in open communication with the accumulator 6. The pipes 46 are provided with branches 47, 48 which lead to opposite ends of a piston chamber 49, this chamber being provided with a piston, the piston rod of which is connected with or is formed in one piece with the yoke 33 before referred to.

With the construction as described, it will be understood that as the tension on the web increases the roll 35 will be forced down, thus operating the cock controlling levers 115 44. The levers will, therefore, be moved in such a way as to admit the fluid under pressure through the branch 48 to the piston chamber 49, so that the piston is driven forward, this driving the controlling cone 31 120 into the roll 2. As the cone is driven into the roll 2, the sections 30 are forced away from the center of the roll, thus increasing the size of the roll and, as the roll is continuously driven, increasing its surface 125 speed. When, however, the tension on the web decreases, the roll 35 will rise and through the connections described, withdraw the cone from the roll 2, thus decreasing its size and its surface speed. As the roll 130

varies in size, therefore, its surface speed will vary, and its driving effect will vary, so that the web will be properly pulled off the roll under varying tension conditions.

5 Changes and variations may be made in the construction by which the invention claimed is carried into effect. The invention claimed, therefore, is not to be limited to the particular construction hereinbefore described and illustrated in the accompanying drawings.

What is claimed is:

1. A driving mechanism for paper rolls of printing machines including in combination a roll support, a continuously running driver roll, means including a source of fluid pressure for maintaining the driving engagement between the driver roll and the paper roll as the paper roll decreases in size, and fluid pressure operated means controlled by the web tension for varying the surface speed of the driver roll.

2. A driving mechanism for paper rolls of printing machines including in combination a roll support, an expandible driver roll, means for maintaining driving engagement between the driver and the paper roll as the paper roll decreases in size, a web tension, and means controlled by the tension for varying the size of the driver roll.

3. A driving mechanism for paper rolls of printing machines including in combination a paper roll support, a source of fluid pressure, a continuously running driver roll, connections from the source of fluid pressure whereby the driving engagement is maintained between the driver roll and the paper

roll as the paper roll decreases in size, a web tension, and connections between the source of fluid pressure and the driver roll controlled by the tension for varying the surface speed of said roll.

4. A driving mechanism for paper rolls of printing machines including in combination a roll support, an expandible driver roll, a source of fluid pressure, connections from the source of fluid pressure whereby the driving engagement between the driver roll and the paper roll is maintained as the roll decreases in size, and connections from the source of fluid pressure controlled by the web tension for varying the size of the driver roll.

5. A driving mechanism for paper rolls of printing machines including in combination a roll support, a continuously running expandible sectional driver roll, a source of fluid pressure, connections from said source of fluid pressure for maintaining the driving engagement between the paper roll and the driver roll as the paper roll decreases in size, a controller for varying the position of the sections on the driver roll, a web tension, and connections from the source of fluid pressure controlled by the tension for operating the controller.

In testimony whereof, I have hereunto set my hand, in the presence of two subscribing witnesses.

GEORGE W. CHURCH.
